United States Patent Office.

MARK SAFFORD, OF BOSTON, MASSACHUSETTS.

Letters Patent No. 77,536, dated May 5, 1868.

IMPROVED SOAP-HOLDER.

The Schedule referred to in these Letters Patent and making part of the same.

TO ALL TO WHOM THESE PRESENTS SHALL COME:

Be it known that I, MARK SAFFORD, of Boston, in the county of Suffolk, and Commonwealth of Massachusetts, have invented a new and useful Soap-Holder, or means of retaining a cake of soap in convenient proximity to a person's hand while washing; and do hereby declare the following to be a full, clear, and exact description thereof, due reference being had to the accompanying drawings, making part of this specification, and in which—

Figure 1 is a perspective view, and

Figure 2 a vertical section of a soap-holder as I intend to construct it.

My present invention is of that class which relates to means for holding a cake of soap in convenient proximity to a person's hand while washing at a tub or other vessel, and which is affixed to or removed from such vessel at pleasure or as occasion requires; the object of this invention being to provide greater security or a more firm support for the device when fixed upon the vessel than has been heretofore accomplished, as well as to allow the water resulting from the drainage of the soap to flow into the tub or vessel, instead of upon the floor.

The invention consists in a flat plate, constructed preferably of cast metal, and enclosed upon its three outer sides with a raised ledge, for preventing the soap from slipping therefrom, such plate being provided on its under side with a means of attachment to the vessel, substantially as hereinafter described.

In the drawings accompanying this specification, *a* denotes a flat plate, made, as before observed, preferably of cast metal, and as being enclosed upon its three outer sides, with a raised ledge, *b*, such ledge serving to prevent the soap from slipping off the plate.

The inner edge of the plate *a* is to be provided with a series of teeth, *c c*, &c., or their equivalents, for preventing slipping of the soap from the plate at this side, while the interstices, *d d*, &c., between the teeth, allow of a drainage of the soap, and of the escape of the water from the soap into the tub or vessel to which the device is attached.

Furthermore, the inner edge of the plate *a*, and at the centre of the same, or thereabouts, is constructed, with two depending projections or feet, *e e*, at a small distance apart, these feet serving to clasp the inner face of the upper edge of the vessel, and disposed with respect to the upper surface of the plate in such manner as to hold the plate at a slight horizontal inclination outward, in order to insure a flow of water from the soap toward the vessel.

The means of clamping the device to the vessel consists, in connection with the feet *e e*, of a bolt, *f*, sliding freely in supports *g g'*, hanging from the under side of the plate *a*, and centrally thereof, the inner end of such bolt, and in advance of the support *g*, being furnished with an ear, *h*, as represented, the bolt and ear being advanced toward the feet *e e*, by the action of a coiled spring, *i*, which encompasses the bolt, and is disposed between the supports *g g'*, the inner end of such spring bearing against a collar, *j*, fixed to the bolt, and its opposite end abutting against the support *g'*.

The bolt *f* allows the device to accommodate itself to vessels whose sides vary in thickness.

As its mode of application and its use is so simple, and will so readily manifest itself to intelligent persons, further explanation is not considered necessary.

What I consider to be novel, and as of my invention, and desire to secure by Letters Patent of the United States, is—

The combination, with the soap-dish, and one or more projections or legs *e e* thereon, of a bolt or clamp, and spring for actuating the same, arranged and operating in connecting with the said legs, substantially in the manner and for the purposes shown and set forth.

MARK SAFFORD.
